UNITED STATES PATENT OFFICE.

EDWARD J. LUTTRELL, OF NEW YORK, N. Y.

PLASTIC-BLOCK MOLD.

1,339,270.

Specification of Letters Patent.

Patented May 4, 1920.

Application filed August 15, 1917. Serial No. 186,384.

To all whom it may concern:

Be it known that I, EDWARD J. LUTTRELL, a citizen of the United States, residing at New York, in the county of New York and 5 State of New York, have invented certain new and useful Improvements in Plastic-Block Molds, of which the following is a specification.

This invention has relation to plastic block 10 molds of the type having hingedly connected sides and has for an object to provide cores and means for supporting the same in the mold whereby openings may be formed in the block.

15 With the above and other objects in view, as will be apparent as the description proceeds, the invention consists in the novel combination and arrangement of coöperating elements as hereinafter more specifically 20 set forth, pointed out in the appended claims and shown in the accompanying drawing.

Referring more particularly to the drawings in which similar reference characters designate corresponding parts throughout 25 the several views,

Figure 1 is a plan view of the mold in set- 30 up position upon the table,

Fig. 2 is a side elevation thereof,

Fig. 3 is a rear end view,

Fig. 4 is a front end elevation,

Fig. 5 is a plan view of the mold with cer- 35 tain of the dividers and partition members positioned in the mold to divide the same into three compartments of equal size for the formation of three blocks for use as in- 40 closure foundation tier blocks, the core hole forming rods being also shown in proper position,

Fig. 6 is a view similar to Fig. 5, showing 45 the mold adapted for making tier founda- 50 tion blocks, the core hole forming rods being also shown in proper position and members 23 omitted,

Fig. 7 is a view similar to Figs. 5 and 6, 55 showing the mold set for producing three tier foundation blocks of another size, other core hole forming rods being shown in position in this view,

Fig. 8 is a plan view of the mold, showing 60 the same assembled for producing six lot markers,

Fig. 9 is a view showing the mold as- 65 sembled for producing two headstone foun- dation blocks,

55 Fig. 10 is a view showing the mold as- sembled for producing two headstone blocks.

Referring more particularly to the drawings, 1 designates the table, which is of a length and width greater than the length and width of the mold and has an end strip 60 or abutment 6 mounted upon its upper face and extending across one end, which will be hereinafter termed the rear end. The table 1 is also provided with longitudinal strips 65 or abutments 7 on its upper face to coöperate 70 with the strip or abutment 6 in holding the body of the mold in proper position upon the table 1 when closed.

The body of the mold consists of an end member 8 which will be termed the rear end, 70 longitudinal or side members 9 hinged to the rear end member 8, and a front end member 10 which is hinged to one of the side members 9. The front end member 10 carries a pivot latch member 11 which is adapted for 75 interlocking engagement with the stationary latch member 12 projecting from the remaining side member 9 of the body. A stationary handle 13 is mounted upon the latch member 11 for the purpose of moving the 80 same into and out of engagement with the stationary latch member 12. The latch member 12 is preferably provided with a trans- 85 verse slot 14 in one edge to receive the piv- uted latch member 11, as will be readily un- derstood by referring to the drawings.

The hinges employed for connecting the side members 9 with the rear end member 8, are designated on the drawings by the nu- 90 meral 15 while the hinges employed for con- necting the front end 10 with one of the side members 9, are designated by the numeral 16. Handles 17 are also mounted upon the outer faces of the side members 9, in order 95 that the body of the mold may be readily placed upon or removed from the table 1.

While the body of the mold may be of any suitable size, I prefer to construct the same in such manner as to provide a cham- 100 ber or compartment which will be approxi- mately 4 ft. 1 in. in length, 16 in. in width and 16 in. in depth, in order that the blocks of the proper sizes may be produced by this mold, the dividers and reducing members serving to divide the compartment or cham- 105 ber into a number of compartments or chambers of equal size when the dividing and reducing members are properly ar- ranged within the mold body.

When it is desired to produce three 110 foundation tier blocks of 12x12x16 in. the main compartment of the mold must be

divided into three compartments by inserting the two transverse dividing plates 18, the vertical edges of which engage in the vertical grooves 19 provided for the same 5 in the inner faces of the sides 9 of the mold body, as clearly shown in Fig. 5 of the drawings. The transverse dividing plates 18 should be approximately one-half an inch in thickness, thereby separating the main 10 compartment into three compartments of 16 in. in length. After the plates 18 have been placed in position, the longitudinal filling blocks 22 are placed in one side of the compartments and the transverse filling 15 blocks 23 are placed in the ends of the compartments. The depth of the compartments, however, will remain at about 16 in. The reducing members 22 and 23 have knobs 24 and 25 respectively, by means of which they 20 may be readily placed in position or removed. Transverse arms 26 are also pivoted to the reducing members 22 to extend transversely across the three compartments, the transverse arms 26 being held in position 25 by removable pins 27 or the like, which extend through the free ends of the arms 26 and into one of the side members 9. The arms 26 are provided with openings 28 above openings 29 in the table 1 to receive 30 removable vertical core opening forming rods 30 for forming core holes in the corners of the closure foundation pier blocks during formation of the latter within the three compartments. After the blocks have been 35 formed, the core forming rods may be withdrawn, the arms 26 released and the mold latch 11 released, after which the mold body may be readily raised from upon the table 1. The reducing members 22 and 23 will 40 then fall away from the blocks. The dividing plates 18 may be withdrawn before opening of the mold body or after removal of the same from the table 1, as desired.

When it is desired to employ this device 45 for forming three pier foundation blocks, the mold body is placed upon the table 1 in the same manner as previously described and the dividing plates 18 are positioned in the mold body in the same manner. The 50 longitudinal reducing members 22 are also placed in the same position as previously described, but the transverse reducing members 23 are omitted. This arrangement of the removable parts results in the provision 55 of three compartments or chambers for the formation of the pier foundation blocks. In this form of block, however, the vertical core hole forming rods 30 are omitted and in place of these rods, I employ the long or 60 longitudinally extending core hole forming rods 33 which are extended through the openings 34 in the opposite end members 8 and 10 of the mold body. The arms 26 are employed in the same manner as described 65 in the foregoing paragraph, to support the

longitudinal reducing members 22 in position during the operation of molding the blocks. This operation may be readily understood by referring to Fig. 6 of the drawings.

When it is desired to produce three pier foundation blocks, it is only necessary to employ the two dividing plates 18 and short transverse core hole forming rods 30, previously mentioned, which latter should be 75 positioned in the transverse openings 35 in the sides 9 of the mold body. The dividing plates 18 are positioned the same as in the two previously described operations.

In order to produce with one operation, six lot markers, the dividing plates 18 are positioned as previously described and longitudinal vertical dividing plates 36 are employed to divide the mold longitudinally, 85 the opposite ends of the dividing plates 36 being engaged in the grooves 18' in the sides of the dividing plates 18 and the grooves 8' and 10' in the end body members 8 and 10 respectively. The arrangement of the parts of the device for the production of the lot markers is illustrated in Fig. 8 of the drawings.

In order to produce two headstone foundation blocks, the two transverse dividing plates 18 are placed in the center of the body with their vertical edges engaged in the wide vertical slots 40 in the inner faces of the sides 9 of the body. This will result in the production of two headstone foundation blocks of practically two feet in length and sixteen inches by sixteen inches in width. The short transverse core opening forming rods 30 should also be employed in this operation, as clearly shown in Fig. 9 105 of the drawings.

When it is desired to produce two curbstone blocks, the long longitudinal vertical dividing plate 41 is employed to divide the body into two compartments of equal size. 110 The longitudinal core hole forming rods 33 may also be employed in this operation, as shown in Fig. 10 if desired.

I claim:

1. A plastic block mold including a table 115 provided with perforations arranged in series, a mold removably mounted upon said table, dividing means for said mold, compartment reducing members for said mold, supporting means for said reducing members, said supporting means being provided with perforations adapted to register with said first mentioned perforations, core hole forming rods adapted to be engaged through the registering perforations, and finishing 120 members adapted to be removably positioned in the compartments of said mold to shape and finish the ends of the blocks formed in said compartments.

2. A plastic block mold having alined end 130

apertures and including a table having apertures, dividing means for said mold, reducing blocks located in said mold, perforated strips above the mold and secured at their ends to the mold and reducing blocks, and core rods extending through the end apertures and through the strips and table apertures.

3. A plastic block mold including side and end members each having alined apertures,

transverse dividing members, defining compartments, filling blocks for said compartments having apertures, and core rods extending through the apertures.

In testimony whereof I affix my signature 15
in presence of two witnesses.

EDWARD J. LUTTRELL.
